FRED EVANS, OF SUMMIT, NEW JERSEY, ASSIGNOR TO PATENTED DEVICES COMPANY, OF NEW YORK, N. Y., A CORPORATION OF NEW JERSEY.

SEALING DEVICE.

1,146,754.

Specification of Letters Patent. Patented July 13, 1915.

Application filed April 14, 1913. Serial No. 760,962.

To all whom it may concern:

Be it known that I, FRED EVANS, residing at Summit, in the county of Union and State of New Jersey, have invented certain new 5 and useful Improvements in Sealing Devices, of which the following is a specification.

This invention relates to a sealing device and a particular object thereof is to provide 10 a simple, inexpensive and efficient sealing device for tags and the like, or for sealing car doors and the like, or for various other purposes where a quick and efficient sealing device is desirable.

15 To this end the device comprises a piece of sheet metal cut into appropriate form, having one end provided with an eye and having its other end adapted to be projected through the eye and to be subsequently manipulated so as to positively prevent 20 its retrogressive movement through the eye, the intermediate portion of the device forming a closed loop such as may extend about two or more members desired to be 25 sealed together.

In the drawings, Figure 1 is a perspective view of a shipping tag having my sealing device applied thereto and showing the method by which the same is sealed; Fig. 2 30 is an elevational view of the sealing device detached; Fig. 3 is a view similar to Fig. 2, but illustrating a modification, Figs. 4, 5 and 6 illustrate various ways in which the sealing end of the device may be formed for 35 improving the quality of the seal; Figs. 7 and 8 are perspective views illustrating forms of my sealing device capable of attachment to shipping tags and the like without the use of tools, or with more despatch 40 than the structures of the other figures; Figs. 9 and 10 are fragmentary detailed sectional views taken substantially on the planes of lines IX-IX and X-X respectively, of Figs. 1 and 8; Fig. 11 is an enlarged fragmentary perspective view of a 45 portion of the structure shown in Fig. 4, illustrating the probable shape assumed in the process of using the structure; and Fig. 12 is an enlarged detailed sectional view.

50 Referring to the drawings for a detailed description of the structure illustrated, and particularly to the structure shown in Figs. 1, 2 and 9, the reference numeral 1 indicates

an elongated piece of sheet metal, preferably thin and easily bent, such as thin tin 55 or brass. This piece of metal is preferably tapered throughout its length, for a purpose presently to be referred to, and at its larger end, as 2, is formed with an aperture 3, the material surrounding the aperture 3 being 60 further enlarged and provided with tangs 4 whereby the larger end of the member may be rigidly attached to a piece of cardboard or the like serving, for instance, as a shipping tag, the tangs 4 being forced 65 through the cardboard and turned upon themselves in a well understood manner, as shown in Fig. 1. The cardboard is obviously apertured adjacent the aperture 3, and the opposite or smaller end 5, of the sealing 70 device, is adapted to be passed through the aperture 3 after first having been engaged about an article to be sealed, for instance the article 6 of Fig. 1, and that portion of the smaller end 5 which projects through 75 the aperture 3 is adapted to be twisted, as shown in Fig. 1. The relative shoulder portions formed by the twists and turns of the projecting end 5 will positively prevent retrogressive movement. The aperture 3 is 80 only sufficiently wide to easily accommodate the thickness of the metal and it will therefore be practically impossible to straighten out the twisted end 5 again so that it could be withdrawn without indicating clearly 85 that it had been tampered with.

Owing to the taper of the piece of metal, and the relative length of the aperture 3, it will be impossible to move the end 5 through the aperture beyond a given point. In the 90 drawings, Fig. 2, this point is indicated at 7, the width of the piece of metal at the point 7 being equal to the length of the aperture 3. In this manner my sealing device is rendered proof against second use, 95 that is, it is impossible, for instance, for an unauthorized person to cut off the twisted portion in order to unseal the device, and subsequently draw through a new section to be twisted.

100 In Fig. 3 I have illustrated a structure wherein this provision against second use is more positively emphasized. In this structure I employ a positive shoulder, as 8, that portion, as 9, of the piece of metal beyond 105 the shoulder 8 being just wide enough to

pass through the slot 3, and the main portion, as 10, of the piece of metal being much too large to pass through the slot 3.

In Figs. 4, 5 and 6 I have illustrated means formed upon the sealing end whereby a more positive seal may be secured incidental to the twisting shown in Fig. 1. In Fig. 4 this means comprises one or more transverse slits 11 cut inwardly from the opposite edges of the metal whereby when the metal is twisted the slits will open and form positive square shoulders as shown in the enlarged view Fig. 11. In Fig. 5 I have shown a plurality of struck-up tongues 12. When the metal of Fig. 5 is twisted the tongues 12 will project in a manner to form positive shoulders. These struck-up portions 12 are of a spring, or resilient, character, and, while they are easily inserted through the aperture 3, they positively prevent retrogressive movement even without twisting the projected portion. In this respect they may serve as temporary connecting or sealing means, and may be employed in association with the structures of the other figures, if desired. Prior to twisting the projected portion, the tongues 12 may be easily pressed downward by the finger, if desired, in order to detach the end. Obviously, if the tongues are not desired as a temporary connecting means but merely to provide portions which will spread apart and form shoulders when the metal is twisted, then they may normally lie flush with surrounding surface, rather than as illustrated.

In Fig. 6 I have shown a series of heads or enlargements, as 13. When the metal of Fig. 6 is twisted, the enlargements 13 will form positive shoulders in much the same manner as the slits 11 of Fig. 4.

In Fig. 7, I have illustrated my sealing device constructed without the tangs 4. In this modification the body portion of the device is inserted through an aperture, as 14, formed in the shipping tag or the like, or the device may be placed around any article or articles intended to be sealed, and the sealing end introduced through the aperture 3 and twisted the same as shown in Fig. 1.

In Fig. 8 I have shown my sealing device as particularly adapted for application to shipping tags and the like. In this modification one end of the device is folded upon itself and provided with mating apertures, and is cut away, as at 15, to form a sort of groove into which an ordinary shipping tag may be inserted, and held so as to dispose its aperture to mate the apertures of the sealing device. The sealing end of the device may then be passed through all of the apertures and seal the whole together. This structure, as well as the structure of Fig. 7, may obviously be applied to tags and the

like without use of tools of any description, whereas the structures of the other figures are preferably attached by some type of tool particularly adapted for clenching the tangs 4.

In all of the structures the actual sealing operation, that is the operation of inserting the sealing end through the aperture 3 and of twisting the sealing end to prevent retrogression, is easily and conveniently accomplished without tools and results in a positive and efficient seal incapable of release, without revealing any effort at tampering. Here it should be noted that the material of which the device is constructed is preferably of such temper or texture as to resist bending or twisting in opposite directions, without fracture, or even entire breaking off of the member beyond the point of the bend sought to be reversed. This point is especially apparent in connection with the structure of Fig. 4, and is also apparent in Fig. 6. In Fig. 4 the slits 11 extend inwardly from the edge of the member and materially reduce the cross-sectional area of the member at that point. In bending the structure, the bends will naturally be sharp at the points of these slits, as clearly shown in Fig. 11, and efforts to straighten out, or reverse, such sharp bends will quickly fracture the already weakened material and give positive evidence of tampering. Though it is obvious that the aperture 3 may be formed by simply cutting away a portion of the material, it is preferable that the aperture be formed in a manner to provide a pyramidal pocket having relatively inclined walls with the aperture at their apex, as shown in the detail view, Fig. 12. These walls may be readily formed, without special care, if an edged tool is employed to form the aperture, the tool being thrust through the sheet metal sufficiently far to form the aperture without cutting away any of the metal, the metal from the aperture being bent back to form the inclined walls. The inclined walls will serve as a convenient means for leading or directing the sealing end of the device into the aperture. The aperture itself may be therefore quite small without being objectionably hard to find. It is obvious that it would be practically impossible to withdraw the sealing end, after having been once twisted, for the reason that even the slightest irregularity in the cross-sectional contour of the sealing end would form a more or less prominent shoulder or stop, which would be engaged by the out-turned edges of the aperture.

As many changes could be made in the above construction and many apparently widely different embodiments of this invention could be made without departing from the scope thereof, it is intended that all

matter contained in the above description or shown in the accompanying drawing shall be interpreted as illustrative and not in a limiting sense. It is also to be understood 5 that the language used in the following claims is intended to cover all of the generic and specific features of the invention herein described and all statements of the scope of the invention, which as a matter of language, might be said to fall therebetween.

Having thus described my invention, what I claim as new and desire to secure by Letters Patent, is:—

1. In a device of the class described, the combination with a shipping tag or the like, of a sealing member having a portionlapping a portion of the shipping tag, thelapping portions of said tag and sealing member being formed with mating apertures, means detachably retaining the sealing member and shipping tag inlapping relation, the sealing member having a portion projected through said mating apertures, and means for preventing withdrawal of 15 said projected portion, comprising juxtaposed parts thereon normally alined to facilitate movement through said mating apertures, and said projecting portion being twisted to spread said juxtaposed parts 20 away from each other and out of alinement, so that one of said juxtaposed parts forms a shoulder, whereby to seal the mentioned portions of the sealing member together and, at the same operation, to seal the sealing 25 member to the shipping tag.

2. A sealing device comprising a part having an aperture formed therethrough, and a second part adapted to be projected through said aperture, the projected portion of said second part having juxtaposed parts normally alined longitudinally of said projected portion to facilitate movement of said juxtaposed parts through said aperture, and said projected portion being twisted to 30

spread said juxtaposed parts away from each other and out of alinement so that one of said juxtaposed parts forms a shoulder to prevent retrogressive movement through said aperture.

3. A sealing device comprising a part 50 formed with an aperture adjacent one end and having its opposite end adapted to be projected through said aperture, the projected portion of said opposite end having a slit formed transversely thereof opening 55 through the marginal edge of said projected portion, and the juxtaposed parts at opposite sides of said slit being normally alined longitudinally of said projected portion to facilitate movement of said juxtaposed 60 parts through said aperture, and said projected portion being twisted to spread said juxtaposed parts away from each other and out of alinement so that one of said juxtaposed parts forms a shoulder to prevent 65 retrogressive movement through said aperture.

4. The combination with a shipping tag or the like, having an aperture formed therein, of a reinforcing member for said tag, 70 having an aperture registering with the aperture in the tag, tangs formed upon said reinforcing member spaced from the aperture thereof serving to retain said reinforcing member and said tag in position with 75 said apertures registering and an extension projecting from the outer edge of said reinforcing member folded to form a loop and having its outer end thrust through said mating apertures and twisted to form a 80 shoulder to prevent retrogressive movement through said mating apertures.

In testimony whereof I affix my signature in the presence of two witnesses.

FRED EVANS.
